R. HINCHLIFF

FRINGE AND METHOD OF MAKING

Filed Sept. 1, 1922

UNITED STATES PATENT OFFICE.

RALPH HINCHLIFF, OF ROCKFORD, ILLINOIS, ASSIGNOR TO BURSON KNITTING COMPANY, OF ROCKFORD, ILLINOIS, A CORPORATION OF ILLINOIS.

FRINGE AND METHOD OF MAKING.

Application filed September 1, 1922. Serial No. 585,728.

To all whom it may concern:

Be it known that I, RALPH HINCHLIFF, a citizen of the United States residing at Rockford, in the county of Winnebago and State of Illinois, have invented certain new and useful Improvements in Fringe and Methods of Making, of which the following is a specification.

This invention relates to textile fringes 10 of the general character employed for ornamental purposes and aims to provide a novel textile fringe and an improved method of making same.

Fringes of this general character have heretofore, as far as I am aware, been woven. My present invention, however, aims to provide a knitted fringe which will be strong and durable, as well as attractive in appearance, which will possess the elasticity inherent in knitted structures, and which is not present in woven fabrics, and one which will be relatively soft and flexible and which can be economically manufactured.

Other objects and advantages of this invention should be readily appreciated as the same becomes better understood by reference to the following description when considered in connection with the accompanying drawings.

Referring to the drawings:

Fig. 1 is a fragmentary face view of a fringe fabric made in accordance with my invention;

Fig. 2 is an edge view thereof;

Fig. 3 is a view similar to Fig. 2 on an enlarged scale; and

Fig. 4 is a similar fragmentary view still further enlarged.

A fringe manufactured in accordance with my invention is knit on a flat bed machine, the needles on the opposite beds being utilized in predetermined sequence, as will be explained. The fringe fabric comprises two or more knitted strips, indicated generally on the drawings by reference characters 5 and 6, the strips being spaced apart and connected by floating yarns 7 which are adapted to be severed between the strips so as to form the fringe proper.

Each knitted strip may comprise one or more knitted webs, and for purposes of illustration, I have shown the strip 5 as comprising three webs, while the strip 6 comprises but one web. Any desired number

of webs, however, may be incorporated in a strip which forms the body or fabric portion of the fabric from an edge or edges of which the unknitted yarns 7 project.

In knitting the fringe and starting at one side of the machine, a predetermined number of needles on one bed are operated in sequence to produce the ply 8, the opposed needles on the opposite bed remain idle during this operation. The yarn is then carried across to the opposite bed where it is acted upon by a series of needles on that bed to produce the ply 9, the opposed needles on the first bed remaining idle during this operation, whereupon the yarn is returned to the first bed and knitted to produce the ply 11 and is then knitted by one or more needles operating in alternation from the opposite beds to form a chain or binding stitch 12. The yarn is then floated a predetermined distance along the beds, producing the unknitted yarns 7, whereupon at a predetermined distance from the strip 5 a chain or binding stitch 13 is produced and then the ply 14 is formed. This operation is continued across the machine, producing alternate knitted strips and floating yarn portions, each of any desired width, the strips comprising as many webs as may be desirable. Upon the return course the same needles are utilized, thus adding another course to each of the plies 14, 11, 9 and 8 in succession, and the yarn may be carried back and forth across the machine and knit into these plies as many times as may be desirable before changing. I have found, however, that for practical purposes four courses knit in each web before changing produce a very satisfactory structure.

When a change is desired the needles which were previously utilized are held idle while the opposed needles which were previously idle are thrown into operation. The yarn is, therefore, first knitted to form the ply 15, then crossed over to the opposite bed to form the ply 16, thence back forming the ply 17, then incorporated in the chain 12, then floated to the next strip where the ply 18 is knit, and so on across the machine, the yarn being knit alternately by needles on the opposite beds and being caused to float between the knitted strips.

The knitted strips, therefore, comprise one or more webs, each consisting of two opposed plies, the webs being joined together

2

at their edges by the yarns which cross from one ply of the fabric to an alternate ply on the opposite face thereof. The various fabric strips are preferably of plain stitch structure, although, if preferred, they may be formed of draw stitches, tuck stitches, or other stitch formations. A fringe fabric thus formed comprises spaced double ply knitted strips each consisting of one or more webs, the strips being connected by floating yarns. These yarns are then cut at any desired point between adjacent strips, leaving the yarns attached at one end to a knitted strip and free at the other end so as 15 to form the fringe proper.

Viewing Fig. 1, the yarns may be cut along the line *a*, *a* intermediate the knitted strips, producing at the selvedge of the fabric a single edge fringe and between the selvedges a plurality of double edge fringes. If preferred, however, the yarns may be cut close to one edge of each strip, thereby producing a series of single edge fringes. The fabric strips themselves and the method of producing the same are not claimed herein as the fabric per se forms the subject matter of my co-pending application, Serial No. 585,-724, filed September 7, 1922.

I claim:

30 1. A knitted elastic fringe consisting of a knitted body comprising, a plurality of interlocked knitted plies, and a fringe at each edge thereof formed by the yarns of the body extending in unknit condition beyond said edges.

2. A knitted fringe comprising, a strip of knitted fabric consisting of a plurality of interconnected plies the yarns of which the fabric is knit being extended in unknit condition beyond the edges of said strip 40 whereby to provide a double edge elastic fringe.

3. A fringe fabric comprising, a series of spaced apart knitted double ply strips the plies of which are interlocked at the 45 edges of the strips, said strips being connected by unknit yarns extending beyond the strips and adapted to be severed between the strips.

4. A fringe fabric comprising, a plurality 50 of knitted strips spaced apart and connected together by the yarns of which the strips are composed extending in unknit condition between the strips and adapted to be severed so as to project freely from the edges of 55 the strips.

5. The method of making a knitted fringe which consists in alternately knitting double 60 ply fabric strips and floating the yarns of which the strips are formed to thereby produce knitted strips connected by floating yarns adapted to be severed so as to thereby produce individual strips of fringe.

6. The method of making a knitted fringe, which consists in knitting double ply fabric 65 strips, interlocking the marginal stitches of the plies of each strip, floating the yarns between the strips and severing said floating yarns.

RALPH HINCHLIFF.
